Nicholas H. Wirtz

UNITED STATES PATENT OFFICE.

NICHOLAS H. WIRTZ, OF WATERTOWN, SOUTH DAKOTA.

COMBINATION LIQUID-LOCK FOR AUTOMOBILES.

1,239,997.

Specification of Letters Patent. Patented Sept. 11, 1917.

Application filed November 14, 1916. Serial No. 131,243.

To all whom it may concern:

Be it known that I, NICHOLAS H. WIRTZ, a citizen of the United States, residing at Watertown, in the county of Codington and 5 State of South Dakota, have invented a new and useful Combination Liquid-Lock for Automobiles, of which the following is a specification.

This invention relates to valves, but more 10 particularly to a combination or permutation valve having for its object to close the flow of liquid from its source of supply and the invention has particular and special application to a gasolene or other fluid valve 15 for automobile motors and other internal combustion motors whereby the motor may be effectually locked against starting or continuous operation by the will of the operator, in such manner that the motor can 20 not be surreptitiously started or operated.

With this object in view the invention consists in the novel construction and arrangement of the valve and particularly in the construction and arrangement of the axially 25 movable fluid passage closures in combination with the permanent or stationary members with which the axially movable closures coact.

The invention also consists in certain 30 other novel details of construction and in certain combinations of parts, all of which will be first fully described and afterward specifically pointed out in the appended claims.

35 Referring to the accompanying drawings—

Figure 1 is a vertical sectional view through a valve constructed in accordance with this invention, and

Fig. 2 is a top plan view of the same.

40 Like numerals of reference indicate the same parts throughout the two figures, in which—

1 indicates an annular substantially ring-shaped member having a gasolene or other 45 fluid port or passage 1' to which the source of liquid supply is piped in any approved manner. The said annular member 1 is provided with an annular recess 2' in which a sleeve 2 is threaded as shown in Fig. 1, the 50 said sleeve 2 having formed thereon at its upper end a dish-shaped portion 3 of a formation as shown in Fig. 1, said dish-shaped portion 3 terminating in a flange 3'.

Threaded on the bottom portion of the 55 annular ring-shaped member 1 is a substantially funnel-shaped member 4 having

threaded connection 4' for the fuel or liquid line, it being understood that this valve is interposed at a convenient position in the fuel or liquid line and between the source 60 of supply of the fuel or liquid and the ultimate liquid or fuel receiving or dispensing apparatus, which in internal combustion engines would be a carburetor or other air and gas mixing device. 65

Disposed internally of the annular ring-shaped member 1 is a sleeve 8 having formed on its lower end a flange 8' to be permanently connected to the annular ring-shaped member 1 by means of fastenings 19. 70

Disposed internally of the annular ring-shaped member 1 and within the sleeve 8 is a similar sleeve 12, itself having on its bottom a flange 12' lying on and against the flange 8' and permanently fastened to the annular 75 ring-shaped member 1 by the common fastenings 19.

It will be observed from Fig. 1 that each of the permanent and stationary sleeves 8 and 12 are provided with fuel apertures 9' 80 and 10' which fuel apertures 9' and 10' are disposed in line with the fuel or liquid passage or port 1' in the annular ring-shaped member 1, and it will also be seen from Fig. 1 that the sleeve 8 is of such external diameter as to provide an annular space between the sleeve 8 and the annular ring-shaped member 1, while the sleeve 12 is of such external diameter as to provide an annular space between the sleeve 12 and the 90 sleeve 8. From this construction it will be understood that the annular ring-shaped member 1, the outer sleeve 2, the sleeve 8 and the sleeve 12 are stationary and rigid with relation to the gas or fuel line. 95

Disposed within the outer sleeve 2 in the manner as shown in Fig. 1 is an axially movable sleeve or tubular member 6 terminating at its upper end in a flange 7 and being of a thickness of wall to snugly enter the space between the stationary sleeve 8 and the annular ring-shaped member 1, said sleeve or tubular member 6 being provided with a fuel or liquid aperture 6' for alignment with the liquid or fuel port or passage 1' in the annular ring-shaped member 1, the flange 7 of said sleeve or tubular member 6 being provided on its lower surface with a depending stop E for a purpose 100 105 which will be presently described.

Disposed within the axially movable sleeve or tubular member 6 is a similar axi-

ally movable sleeve or tubular member 10, itself being provided at its upper end with a flange 11 and being of a thickness of wall to snugly enter the space between the two 5 stationary sleeves 8 and 12, said sleeve or tubular member 10 being provided with a liquid or fluid aperture 20' for alignment with the liquid or fuel port or passage 1' in the annular ring-shaped member 1, and 10 also for alignment with the liquid or fuel apertures 6', 9' and 10' heretofore referred to, the said flange 11 of the annular movable sleeve or tubular member 10 being equipped with a stop D for a purpose which 15 will be hereinafter fully described.

Disposed within the axially movable sleeve or tubular member 10 and centrally of the device is an axially movable tubular member 16 of an external diameter to insure a close snug fit within the innermost stationary sleeve 12, said central tubular member 16 having its lower end entering the funnel-shaped stationary member 4 and being equipped with nuts 18 and 18 for securing the axially movable parts in proper, relative and operative position. The central tubular member 16 is provided with a liquid or fuel aperture 16' registering with the other fluid or liquid apertures in the 20 two stationary sleeves 8 and 12 and with the two axially movable sleeves or tubular members 6 and 10 in the manner as shown in Fig. 1. The top of the central tubular member 16 is provided with a flat member 35 17 closing the said central tubular member and upon the under-surface of said flat member 17 is a stop A.

Extending horizontally from the dish-shaped member 3 is a supporting plate 14 through which the central tubular member 16 extends and upon the upper face of the plate 14 is a stop B arranged in the path of rotation of the stop A on the central plate member 17, while arranged on the 40 under-face of the supporting plate 14 is a stop C positioned in the path of rotation of the stop D on the flange 11 of the axially movable sleeve or tubular member 10, while arranged on the dish-shaped member 3 is a stop F positioned in the path of rotation of the stop E on the flange 7 of the axially movable sleeve or tubular member 6. From this it will be understood that the 45 stops B, C and F are stationary with relation to the device, while the stops A, D and E are movable with the axially movable sleeve or tubular members 6, 10 and 16.

Positioned between the several axially movable sleeves or tubular members are 50 washers 5, 9, 13 and 15, so as to insure the proper relative position of the parts.

Referring to the flanges 7, 11 and 17 on the axially movable tubular members, reference is made to Fig. 2, wherein it will 55 appear that said flanges are provided

around their peripheries with a series of points 7', 11' and 17', the points on all three of the flanges being of equal number so that they may coincide one with the other in the manner as shown in Fig. 2, 70 while I provide on the flange 3' of the dish-shaped member 3 an arrow 20, indicating a starting point from which the combination is worked out.

Having thus described the several parts 75 of the invention, its operation is as follows:

Upon axial movement of the sleeve or tubular member 6 a predetermined distance, its fuel aperture 6' will register with the fuel or liquid port or passage 1' in the annular ring-shaped member 1, while axial movement of the sleeve or tubular member 10 and the central tubular member 16 will likewise bring their liquid or fuel apertures 10', 16' to register with the fuel apertures 85 in the stationary sleeves 8 and 12 and with the fuel or liquid passage 1' in the annular ring-shaped member 1. When all of these fuel or liquid apertures, in the several axially movable tubular members and in the 90 two stationary sleeves, register one with the other in the manner as shown in Fig. 1, the fuel passes freely through the valve, as will be clearly apparent from an inspection of the accompanying drawings. When, however, one or more of the axially movable sleeves or tubular members 6, 10, and 16 are moved axially, communication between the fuel port or passage 1' and the funnel-shaped member 4 is cut off so that no fuel 95 or liquid can pass from the source of supply through the liquid or fuel line. In order to establish the proper position of each 100 of the axially movable tubular members in order to effect communication through the line, each of the axially movable members is moved to the right or to the left until all of the movable stops A, D and E are in engagement with and in contact with the three stationary stops B, C and F. It will be understood that the stationary stops B, C and 110 F absolutely limit the extent of axial movement of the three axially movable tubular members and that, therefore, the extent of movement of any one of the three 115 tubular members is entirely independent of, and has no bearing upon the movement of its next or other tubular member. When, therefore, all of the tubular members are in locked position against the stationary stops 120 B, C and F, it is only necessary to move first one and then the others of the tubular members a certain predetermined number of points from the arrow 20 in order to establish the necessary communication through 125 the valve. For instance, a movement of the axially movable tubular member 6 three points to the right of the arrow 20, a movement of the intermediate axially movable member 10 five points to the right of the 130

arrow 20 and a movement of the central axially movable tubular member 16 three points to the right of the arrow 20 would bring their liquid or fuel apertures in proper alignment to establish communication between the valves, while, of course, any other combination could be made in order to insure a variation for each valve produced. As a matter of fact it is only necessary to 10 move the three axially movable members a certain predetermined distance from the arrow 20 and then drill a hole through all of the axially movable members and through the two stationary sleeves 8 and 12 in order 15 to produce any desired combination of the valve.

As before stated the movement of any one of the axially movable tubular members has no effect or bearing upon the movement of 20 any other of the tubular members, for as will appear from the foregoing specification taken in connection with the accompanying drawings that there is interposed between the axially movable tubular members the 25 two stationary sleeves 8 and 12. Accidental or unintentional movement of any one of the axially movable tubular members is, therefore, effectually provided against, which makes it possible for the operator to 30 quickly and without loss of time, produce the desired combination or extent of movement of the three axially movable tubular members.

Having thus fully described the invention it is apparent that the same is susceptible to changes and variations in the design, arrangement or construction of the parts and I consider myself clearly entitled 35 to all such modifications as fall within the 40 limit and scope of the appended claims.

What I claim as new and desire to secure by Letters Patent of the United States, is:—

1. A valve of the type described, including an outer stationary casing, a plurality 45 of stationary sleeves within the casing and spaced apart from the casing and from each other, the said casing and the said sleeves being provided with passages through which

liquid may pass, said passages being in alignment one with the other, a plurality of 50 independent axially movable tubular members within the said casing and disposed in close contact with the said plurality of sleeves within the said casing, each of said tubular members being provided with an 55 aperture for the passage of liquid arranged in the same transverse plane as the aforementioned liquid passages, each of said tubular members being provided with means for manual manipulation, a stationary stop for each 60 of said axially movable tubular members and a stop on each of said axially movable tubular members for engagement with the stationary stop for each of the axially movable tubular members to limit the axial 65 movement of each of the axially movable tubular members, the whole being arranged in such manner that upon axial movement of the said axially movable tubular members, the said apertures therein may be 70 brought into alignment with the liquid passages in the casing and in the said stationary sleeves to effect communication through the whole, substantially as described and for the purposes set forth. 75

2. A valve of the type described, including a stationary casing, a plurality of alternate stationary sleeves and axially movable tubular members within the said casing, the said casing and the stationary sleeves being 80 provided with alining passages for liquid, each of the said axially movable tubular members being provided with an aperture in the same transverse plane as the said passages in the casing and in the stationary 85 sleeves, each of the said axially movable tubular members being equipped with means for manual manipulation, the whole arranged in such manner that upon axial movement of the said axially movable tubular members the apertures therein may be 90 brought into alinement with the said passages in the said casing and in the said stationary sleeves to effect communication of liquid through the device. 90
